of Wisconsin

Filed Oct. 14, 1959, Ser. No. 57,930

Term of patent 14 years

(Cl. D81—19)

The figure is a perspective view of a unit heater casing embodying my design.

The rear of the casing is open and the side opposite that shown is substantially the same as the side shown. The bottom is substantially the same as the top shown.

I claim:

The ornamental design for a unit heater casing, as shown and described.
